Inventor
Wesley Farrington

United States Patent Office.

WESLEY FARRINGTON, OF MORRISANIA, NEW YORK.

Letters Patent No. 92,026, dated June 29, 1869.

IMPROVED MAT AND SCRAPER.

The Schedule referred to in these Letters Patent and making part of the same.

To all whom it may concern:

Be it known that I, WESLEY FARRINGTON, of Morrisania, in the county of Westchester, and State of New York, have invented a new and useful article, called a "Combined Mat and Scraper;" and I do hereby declare that the following is a full, clear, and exact description of the construction and operation of the same, reference being had to the annexed drawings, making a part of this specification, in which—

Figure 1 is a perspective view of the article, showing the position of the same when in readiness to be used as a scraper, and

Figure 2, of the same, when in position to be used as a brush or mat.

This article consists of two perpendicular standards, A A, between which, pivoted to them at its lower end, swings a plate, B, with a scraper, C, attached to its top.

Fastened to the inside of this plate is a coarse, stiff brush, D.

At the lower end of the plate is an attachment, E, made with an upper curved side, and well adapted to adjust itself to the toe of a foot, to assist in raising the plate from the position, as shown in fig. 2, to that of fig. 1.

The operation of the above combined mat and scraper is as follows:

The plate B swings between the standards A A by means of pivots at F F, and is kept in the inclined position indicated in fig. 1, by means of small projections G G, attached to the plate, which strike the standards and prevent the plate from falling back. In this position, it can be used as a scraper. At a slight tap of the foot, the plate falls down with the brush uppermost, as in fig. 2, and is held in this position by means of two small projections, H H, attached to the standards. It can now be used as a brush or mat.

Should it be necessary to bring the plate back to the position, as in fig. 1, a slight pressure of the foot upon the curved attachment E will produce the desired result.

Claim.

What I claim as my invention, and desire to secure by Letters Patent, is—

The arrangement of plate B, pivoted to the standards A A, and having scraper C, brush or mat D, and foot-attachment E, constructed as herein described, for the purpose set forth.

WESLEY FARRINGTON.
